US00D583124S

(12) **United States Design Patent**
Stark

(10) **Patent No.:** US D583,124 S
(45) **Date of Patent:** ** Dec. 16, 2008

(54) **FORKLIFT**

(75) Inventor: **Stefan Stark**, Ludwigsburg (DE)

(73) Assignee: **Dr. Ing. h.c. F. Porsche AG**, Weissach (DE)

(**) Term: **14 Years**

(21) Appl. No.: **29/298,958**

(22) Filed: **Dec. 17, 2007**

(30) **Foreign Application Priority Data**

Jun. 15, 2007 (EP) 740402

(51) **LOC (8) Cl.** 12-05

(52) **U.S. Cl.** D34/34

(58) **Field of Classification Search** D34/28, D34/34; 180/89.12, 299, 325, 43.12; 187/222, 187/224

See application file for complete search history.
